(57) **CLAIM**

The ornamental design for a cleaning pen, as shown and described.

DESCRIPTION

FIG. 1 is a front, bottom perspective view of a cleaning pen, showing my new design;

FIG. 2 is a rear, top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an exploded view thereof; and,

FIG. 10 is another exploded view thereof.

The broken lines in the figures illustrate portions of the cleaning pen that form no part of the claimed design.
